ELECTRIC DISCHARGE LAMP AND CONTROLLING MEANS THEREFOR

William James Harris, Newport, England

Application January 2, 1945, Serial No. 571,047
In Great Britain January 5, 1944

1 Claim. (Cl. 315—99)

1

This invention relates to electric discharge lamps, fluorescent or otherwise, and controlling means therefor, of the type in which the lamp consists of an envelope containing gas such as mercury or sodium vapour or neon, with or without a proportion of argon, into the ends of which envelope are sealed two filamentary electrodes (these latter preferably having associated alkaline earth oxides) and in which the controlling means includes an automatically operating or other starting switch which when closed and upon the mains voltage being applied to the lamp, allows current to pass to the electrodes sufficient to raise them to incandescence and to start ionisation of the gas in their immediate vicinity, and when opened effects the breaking of the circuit through the electrodes to permit other means remaining in the circuit to give a high voltage kick or surge through the gas between the electrodes sufficient to start the discharge through the lamp, and has for its object so to devise the controlling means that such lamps can be started and run with efficiency on direct current, even of comparatively low voltage.

In general, in accordance with the invention, the lamp proper is made in any usual manner and the controlling means for the lamp comprises an electromagnetic inductance co-operating with a make-and-break device. This latter forms the starting switch of the control and is connected in the circuit in the position for such switch and comprises a movable armature or its equivalent at least partly of magnetic material, whilst the inductance is such and so mounted in the circuit that it forms the means for inducing the necessary high voltage when, with the lamp connected to the mains, the starting switch is opened. In addition, the inductance and armature are so juxtaposed that when the lamp is connected to the mains the magnetic flux of the inductance is adapted to attract the armature against resilient return means to effect the opening of the starting switch, the said flux being sufficient at all times, even after starting, to maintain the said switch open. Further, the windings of the inductance also act as a limiting device for the current consumed by the lamp.

Preferably, the main switch between the mains and the lamp circuit is of a one-direction rotary type so that the polarity of the electrodes is reversed upon successive lightings of the lamp, to eliminate defects due to electrophoresis.

In most cases and for convenience, the control is included in the structure of the lamp, for example in a compartment at the back of a trough-

2

like or other hood or shade of the lamp, although it may be separate from the lamp.

It will be understood that when the lamp is not connected to the mains, the make-and-break device is held by the resilient return means so that it is closed, in other words the starting switch is closed, and the armature comes at the maximum distance from the adjacent end of the inductance. As a consequence, when the mains switch is next operated, current at mains voltage passes through the two filamentary electrodes, the inductance and the make-and-break device. The electrodes come to incandescence and start the ionisation of the gas in their immediate vicinity. Also, the magnetic flux commences to attract the armature and this latter is moved thereby to break the contact of the starting switch. This causes the voltage surge and if the partial ionisation of the gas has been adequate, then this voltage surge is sufficient to start the discharge of the lamp. The current continues to flow through the inductance and its magnetic flux keeps the armature of the starting switch in the open position.

25 Should, however, the preliminary heating by the electrodes be insufficient, then upon the opening of the starting switch and after the consequent voltage surge no current will continue to flow through the inductance, and as a consequence the armature, not being magnetically attracted, will again be brought by the resilient return means to contact-making position. Thus, a "trembling" action may take place for a short period until the starting ionisation of the gas in the neighborhood of the electrodes is sufficient for the induced high voltage consequent upon an opening of the starting switch, to start the discharge through the lamp.

40 Upon moving the main switch to switch off the lamp, the magnetic flux through the inductance ceases and the armature returns to the contact-making position, in other words the starting switch is closed ready for the next operation of the main switch, and so on. If this main switch is of the one-directional rotary type, then on the next operation the polarity of the electrodes will have been reversed.

In order that the invention may be better understood, it will now be described with reference to the accompanying drawings which are given by way of example only and in which—

Fig. 1 is a somewhat diagrammatic cross sectional elevation of one form of electric discharge lamp and control therefor constructed accord-

ing to the invention, assembled as a unitary structure with a trough-like reflector and shade.

Fig. 2 is a plan of Fig. 1 with parts in section.

Fig. 3 is a diagram of a lamp and control in accordance with the invention when the lamp is not connected to the mains and with the starting switch in the closed position.

Fig. 4 is a similar view to Fig. 3 but showing the lamp connected to the mains and with the starting switch in the open position.

The inductance to be employed in any case, that is to say the number of turns and the gauge of the insulated wire used, depends upon the voltage of the supply and the wattage of the lamp. In a particular case for a fluorescent tubular lamp of standard dimensions, 60" long and 1½" diameter, rated at 80 watts to operate at substantially 230 volts, the inductance comprises six coils. Each coil is a multi-layer coil with a hollow core of desired diameter and is made up from 3283 turns of 27 gauge insulated copper wire, the outside dimensions of the coil being substantially 6" long and 1½" diameter. The complete inductance is constituted by connecting the six coils in series and arranging them end to end in axial alignment.

In the drawings, 5 is the electric discharge lamp of standing dimensions with two-pin bayonet end caps to engage the equivalent sockets of a trough-reflector and shade 6 in any usual manner. The shade at its rear has a compartment 7 which houses an inductance formed by six coils 8 connected in series and arranged end to end in axial alignment as hereinbefore described. It also houses a casing 9 in which the make-and-break or starting switch is located.

The starting switch may take many forms. As diagrammatically shown in Fig. 2, it comprises an armature formed from a stem 10 and head 11 of magnetic material, the stem entering and being adapted to slide in the hollow core of the first coil 8 of the inductance. The head 11 is kept pressed outwards by a spring 12. On the side of the head remote from the spring, this head has a contact 13 which in the closed position of the starting switch is in electrical connection with another contact 14 carried by a fixed conducting support 15 the position of which preferably is adjustable by a screw 16. The spring 12 keeps the contacts 13 and 14 in electrical connection when the lamp is not lit. Any suitable connections are provided so that the contacts 13 and 14 are included in the circuit of the starting switch.

As shown in Figs. 3 and 4, the starting switch is comprised by a pivoted armature 17 having a contact 18 and a head 19 of magnetic material. The contact 18 co-operates with another contact 20 carried by a fixed support 21 the position of which preferably is adjustable by a screw 22. The contacts 18 and 20 are held in electrical connection when the lamp is not lit, by a spring 23 which pulls the armature in one direction and the head 19 is so disposed in relation to the axis and end of the inductance that under the magnetic flux due thereto when the lamp is lit, the armature can move through a small angular distance to separate the contacts 18 and 20 to open the starting switch and remain in this position while the lamp is alight.

Except for the leads 24 to the main switch 25, all the leads between the parts preferably are housed in the lamp structure and are indicated by exterior dotted lines in Fig. 1 and more fully particularised in the diagrams Figs. 3 and 4. From these latter it will be seen that one lead 24 is con-

nected to one end of a filamentary electrode 26 the other end of this electrode being connected to the fixed contact 20 of the starting switch. The armature 17 is a conductor or has an associated conductor and this is connected to one end of the other electrode 27 the other end of this last-mentioned electrode being connected to one end of the inductance, the other end of the inductance being connected to the other lead 24. The first-mentioned lead 24 is connected to a contact 28 of the main switch 25 which is a one-direction rotary starting switch and the other lead 24 to the next contact 29 of the said switch. 30 and 31 are two further contacts of the starting switch to which the mains 32 for D. C. current of desired voltage (230 volts in the particular case under consideration) are connected. The starting switch is symmetrically arranged and the movable conducting parts of the switch are such that the polarity of the contacts 28 and 29 therefore is reversed on successive operations of the switch to bring the lamp into the D. C. circuit; Fig. 3 shows a switched-off position. By movement in the direction of the arrow 33, the switch is brought into the position shown in Fig. 4 to switch the lamp into circuit. By further movement of 45° in the same direction from the position shown in Fig. 4, the lamp is again switched off, and so on. As each successive switching-on reverses the polarity of the contacts 28 and 29 of the switch, the polarity of the electrodes 26 and 27 also is reversed.

In operation it will be understood, with the parts in the position shown in Fig. 3, that immediately the current is switched on by the switch 25 a circuit is completed from the contact 28 of the switch 25 through the filament 26, through the make-and-break contacts 20 and 18, through the armature 17, through the other filament 27, through the inductance comprised by the six coils 8 in series, back to the contact 29 of the switch. This circuit remains completed for an extremely short period, during which however the filaments 26 and 27 are brought to incandescence to start ionisation of the gas in their immediate vicinity. After this has been effected, the magnetic flux of the inductance attracts the armature 17 to separate the contacts 18 and 20 (or 13 and 14, Fig. 2). This induces a very high voltage by the collapse of the magnetic field of the inductance coils and enables the current to overcome the resistance of the gases in the lamp to start the discharge between the electrodes 26 and 27, which latter of course are no longer incandescent.

The parts are now in the position shown in Fig. 4 and now that the gas path is a conductor (represented by the dotted arrows 34, Fig. 4), although the connections from the filaments to the make-and-break switch are no longer in circuit, the said gas path comes in series with the inductance coils 8 so that the magnetism due to the current passing through the said coils keeps the armature 17 attracted, maintaining the contacts 18 and 20 apart. Moreover, the coils 8 also act as a limiting device for the current consumed by the lamp.

When the switch 25 is operated to switch the lamp from the circuit, then the current through the gas path is broken to cause the cessation of the illumination and no current passes through the coils 8, which enables the spring 23 to return the armature 17 to the contact-making position ready for the lamp again to be switched on.

75 Electric discharge lamps, particularly of the

fluorescent type, and controls therefor, in accordance with the invention, in practice have been found highly efficient both from the aspect of consumption and illumination. After lighting, they run without flicker and no part of the lamp or the control has a temperature greater than slightly above room temperature. One such lamp of the standard type hereinbefore mentioned operating at 230 volts on D. C. with the control according to the invention, already has had a total illuminated life of over 5,000 hours, its electrical efficiency being unimpaired whilst its luminous efficiency has fallen off but slightly.

The exact arrangement of the inductance for any particular case will depend upon the voltage and wattage, and further upon the housing capacity for the coils. Generally, the lower the voltage the fewer the total windings of the inductance and/or the thicker the gauge of the wire used. It is preferred to make up the inductance in separate coils such as 8 in the drawings of desired numbers of turns and of a desired gauge wire and to utilise as many of such coils as is desired in any particular case.

In connection with the make-and-break device with its armature, whatever the exact construction, in some cases a damping device may be utilised of the diaphragm or other type and operating by air or other fluid. This acts to delay the opening of the starting switch for a short period, for example a few seconds and then allows a quick break to give the necessary voltage surge.

The system according to the invention enables fluorescent or other electric discharge lamps to be satisfactorily operated either from direct current mains, or batteries, or accumulators, in fact from any D. C. supply and at any convenient voltage. As a consequence of the satisfactory operation of such lamps from D. C. sources, it is possible to utilise these fluorescent or other electric discharge lamps not only in fixed positions such as in streets and buildings, but also in vehicles such for example as trains, trams, omnibuses, motor road vehicles generally, aircraft, shipping and otherwise.

The invention is not limited to the precise forms or details of construction herein described, as

these may be varied to suit particular requirements.

What I claim and desire to secure by Letters Patent of the United States of America is:

- 5   A starting and operating circuit for gaseous electric discharge lamps having two filamentary electrodes sealed into the envelope of the lamp, including an automatically operating starting switch which when closed and upon the supply voltage being applied to the lamp allows current to pass through the electrodes sufficient to raise them to incandescence and to start ionisation of the gas in their immediate vicinity and when opened effects the breaking of the circuit through the electrodes to permit an electro-magnetic means remaining in the circuit to give a high voltage kick through the gas between the electrodes sufficient to start the discharge through the lamp, said starting switch being formed by a 10 make-and-break device held closed when the lamp is unlit and including a movable armature, said electro-magnetic means being formed of an electro-magnetic inductance comprising a coil greater in length than in diameter and having a 15 hollow core arranged with its axis parallel to the axis of the envelope of the lamp, the armature of the starting switch extending movably into said hollow core of the electro-magnetic inductance, the parts being so relatively positioned and constructed that the armature is subject to the magnetic flux produced by the energized inductance to cause the armature to be attracted and drawn 20 farther into the coil to open the starting switch, and spring means for returning the armature to a position in which the latter closes the starting switch upon de-energization of said inductance.
